UNITED STATES PATENT OFFICE.

HARRY W. PUGH, OF NEW YORK, N. Y., ASSIGNOR TO WESTERN ELECTRIC COMPANY,
INCORPORATED, OF NEW YORK, N. Y., A CORPORATION OF NEW YORK.

ADAPTER FOR CALLING DEVICES.

1,414,373.

Specification of Letters Patent. Patented May 2, 1922.

Application filed November 14, 1919. Serial No. 337,911.

To all whom it may concern:

Be it known that I, HARRY W. PUGH, a citizen of the United States, residing at New York, in the county of Bronx, State of New York, have invented certain new and useful Improvements in Adapters for Calling Devices, of which the following is a full, clear, concise, and exact description.

This invention relates to adapters for calling devices and telephone transmitters, and particularly to an adapter providing means for assembling into a self-contained unit, a telephone transmitter and a calling device.

An object of this invention is the provision of a new and an improved adapter of simple construction on which a calling device for automatic telephones and a telephone transmitter can be mounted to form a self-contained unit which can be readily attached to a subscriber's telephone instrument without making any undesirable modification in the instrument, such as screw holes or openings for wires. Another object of this invention is to provide an adapter which can be attached to the transmitter bracket of either a wall type telephone or a desk type telephone.

When a telephone central office is re-equipped and changed over from manual operation to automatic operation, each subscriber's telephone instrument connecting with that office is usually equipped with a calling device or impulse sender such as that described in United States Patent No. 1,161,854 to O. F. Forsberg. It is desirable in such instances that means be provided whereby calling devices can be attached to the subscribers' telephones without the necessity of making any additional holes or otherwise modifying the instruments.

To attach a calling device to an ordinary desk type instrument, such as illustrated in Fig. 1, involves either a very considerable modification of the instrument or the use of a suitable adapter for attaching the calling device.

This invention is an adapter for a calling device and a transmitter comprising a metal base plate formed into a suitable shape. A calling device is attached to one end-portion of said base plate and a transmitter attached

to the other end thereof. A lug integral with said base plate is provided for pivotally attaching it to the transmitter bracket of a telephone and a substantially closed chamber, 55 integral with said metal plate provides protection for the conductors from the calling device and the transmitter.

Referring to the drawing—Figs. 1 and 2 are side and front elevations respectively, 60 showing this adapter applied to a telephone desk stand in which 1 is the desk stand, 2 is a transmitter bracket forming a part of the desk stand, 3 is the adapter, 4 is the lug forming an integral part of the adapter and 65 pivotally attached to the transmitter bracket, 2, 5 is the enclosed chamber for the conductors from the calling device and transmitter, 6 is a calling device and 7 is a transmitter. Fig. 3 is a perspective view of the adapter. 70

This adapter can be applied to a wall type telephone provided with a suitable transmitter bracket as well as to a desk stand.

What is claimed is:

1. A telephone sub-station set including a 75 transmitter, a standard, a calling device, a unitary support comprising a base plate to which said transmitter and calling device are attached, a rearwardly extruded hollow mounting lug integral with said base plate 80 for attaching the support to the standard, and forwardly extending ears on said base plate cooperating with said lug, calling device and transmitter to form an enclosed cord chamber through which conductors may 85 lead from said calling device and the transmitter to said standard.

2. A telephone set comprising a standard, a transmitter, a calling device, and a support for pivotally securing said transmitter and 90 calling device on said standard, said support comprising a base plate, a rearwardly extending lug, forwardly projecting ears cooperating with the transmitter, the calling device and the lug to form a conduit through 95 which conductors may be led from the transmitter and the calling device to the standard.

In witness whereof, I hereunto subscribe my name this 8th day of November, A. D. 1919.

HARRY W. PUGH.
